United States Patent Office.

JOHN H. BELLAMY, OF CHARLESTOWN, MASSACHUSETTS.

Design No. 4,248, dated July 19, 1870.

DESIGN FOR A PICTURE-FRAME.

The Schedule referred to in these Letters Patent and making part of the same.

To all whom it may concern :

Be it known that I, JOHN H. BELLAMY, of the city of Charlestown, in the county of Middlesex and State of Massachusetts, have originated and designed a new and useful Pattern for Picture-Frames, of which the following is a full, clear, and exact description, reference being had to the accompanying photographs making a part of this specification.

The nature of my invention consists of so arranging emblems in open-work, so as to show above space A a crown, B, together with cross keys, C C, there being on the top of crown B a globe, D, surmounted by a cross, E, below space, A, and at the bottom of the frame is an open book, F, with a cross as a bookmark, G, there being crossed and combined with the collection a crook, H, on the right and on the left a miter, J, the whole being inclosed in open ornamental scroll-work.

What I claim as my invention, and desire to secure by Letters Patent, is—

The design or pattern for a picture-frame herein set forth.

JOHN H. BELLAMY.
